UNITED STATES PATENT OFFICE

WILLIAM J. A. BAILEY, OF EAST ORANGE, NEW JERSEY

DESIGN FOR A RADIOACTIVE MATERIAL RAY DISSEMINATOR

Application filed April 24, 1929. Serial No. 30,991. Term of patent 3½ years.

To all whom it may concern:

Be it known that I, WILLIAM J. A. BAILEY, a citizen of the United States, and a resident of the city of East Orange, in the State of New Jersey, have invented a new, original and ornamental Design for Radioactive Material Ray Disseminators, of which the following is a specification, reference being had to the accompanying drawing, forming part thereof.

Fig. 1 represents a front elevation.

Fig. 2 is a plan view, and

Fig. 3 is a side elevation.

I claim:

The ornamental design for a radio-active material ray disseminator, as shown.

WILLIAM J. A. BAILEY.
